United States Patent Office

Des. 208,597
Patented Sept. 12, 1967

208,597

WRITE-ON TAPE DISPENSER

Edward Waltz, Grand Rapids, Mich., assignor to The E. O. Bulman Manufacturing Company, Inc., Grand Rapids, Mich., a corporation of Michigan

Filed Nov. 10, 1966, Ser. No. 4,627

Term of patent 14 years

(Cl. D74—1)

I claim:

The ornamental design for a write-on tape dispenser, as shown.
